(57) **CLAIM**

The ornamental design for a net tape, as shown and described.

DESCRIPTION

FIG. 1 is a front view of a net tape showing my new design;

FIG. 2 is a back view thereof;

FIG. 3 is a side view thereof;

FIG. 4 is a top view thereof; and,

FIG. 5 is an expanded view taken along line 5—5 in FIG. 3; and,

FIG. 6 is a perspective view thereof, in use condition.

The broken line showing of the human body in FIG. 6 is for illustrative purposes only and forms no part of the claimed design.
